UNITED STATES PATENT OFFICE

164,334

TELEVISION TRANSMITTER CONTROL
OPERATORS CONSOLE

Lee Ira Spooner, North Arlington, N. J., assignor
to Allen B. Du Mont Laboratories, Inc., Passaic,
N. J., a corporation of Delaware

Application January 29, 1949, Serial No. 568

Term of patent 14 years

(Cl. D26—14)

To all whom it may concern:

Be it known that I, Lee Ira Spooner, a citizen of the United States, and a resident of N. Arlington in the county of Bergen, State of New Jersey, have invented a new, original, and ornamental Design for Television Transmitter Control Operators Console, of which the following is a specification, reference being had to the accompanying drawing, forming part thereof.

In the drawing:

Figure 1 is a perspective view of the television transmitter control operators console, showing the new design; and

Figure 2 is a plan view of the panel portion of the console, showing the arrangement of the knobs.

The dominant features of the design reside in that portion shown in full lines in the drawing.

I claim:

The ornamental design for a television transmitter control operators console, as shown and described.

LEE IRA SPOONER.
